UNITED STATES PATENT OFFICE.

SAMUEL B. HUSSelman, OF PHILADELPHIA, PENNSYLVANIA.

DESIGN FOR A FENCE-POST.

SPECIFICATION forming part of Design No. 25,283, dated March 24, 1896.

Application filed February 17, 1896. Serial No. 579,656. Term of patent 14 years.

To all whom it may concern:

Be it known that I, SAMUEL B. HUSSelman, a citizen of the United States, residing at the city of Philadelphia, in the county of Philadelphia and State of Pennsylvania, have invented and produced a certain new and original Design for a Fence-Post, of which the following is a specification, reference being had to the accompanying drawing, showing in perspective a post of my design.

The leading feature of my design consists of a post having a cylindriform member integrally formed with an annularly-shouldered member merging into a tapering four-sided member and having at one portion thereof a deflecting parallelepiped member disposed at an angle of about forty-five degrees to the vertical position of the tapering four-sided member.

Referring to the drawing, A represents the cylindriform member.

B represents the annularly-inclined shouldered member.

C represents the four-sided tapering lower member terminating in a pyramidal-shaped point c, and D represents the parallelepiped-shaped projecting member disposed at an angle of about forty-five degrees to the vertically-inclined four-sided member C.

Having thus described the nature and objects of my invention, what I claim as new, and desire to secure by Letters Patent, is—

The design for a fence-post, substantially as shown and described.

In testimony whereof I have hereunto set my signature in the presence of two subscribing witnesses.

SAMUEL B. HUSSelman.

Witnesses:

J. WALTER DOUGLASS,
RICHARD C. MAXWELL.
